UNITED STATES PATENT OFFICE.

ALBERT ABBE GRISWOLD, OF PROVIDENCE, RHODE ISLAND, ASSIGNEE OF ONE-HALF
TO JOHN FRANCIS CHEVALIER, OF BROOKLINE, MASSACHUSETTS.

SELF-GAUGING FLEXIBLE SHINGLE.

Application filed August 10, 1923. Serial No. 656,644.

To all whom it may concern:

Be it known that I, ALBERT ABBE GRISWOLD, a citizen of the United States, residing at Providence, in the county of Providence and State of Rhode Island, have invented a new and useful Improvement in Self-Gauging Flexible Shingles, of which the following is a specification.

My invention has reference to an improvement in shingles and more particularly to an improvement in flexible shingles as shown in United States Patent No. 1,274,410, granted to me August 6, 1918, for flexible shingle.

In the heretofore usual construction of shingled roofs on which flexible shingles are laid diagonally, gauge lines are used for spacing or gauging the shingles in laying the shingles. These gauge lines are usually of cord or string; they are secured at each end to the roof and require skilled labor in accurately placing the gauge lines on the roof. The use of these gauge lines also adds materially to the cost of shingling a roof.

The object of my invention is to improve the construction of flexible shingles adapted to be laid diagonally, whereby each flexible shingle is provided with a shingle laying gauge, thereby eliminating the use and cost of gauge lines heretofore used for this purpose.

A further object of my invention is to construct such a flexible shingle with a shingle laying gauge, so that there is no waste or additional cost in forming the gauge part of the shingle.

Another object of my invention is to reduce the cost of shingling a roof with flexible shingles laid diagonally.

My invention consists in the peculiar and novel construction of a flexible shingle adapted to be laid diagonally, said flexible shingle having a shingle laying gauge and details of construction, as will be more fully set forth hereinafter and claimed.

Figure 1 is a plan view of a portion of a flexible-shingled roof, each of said flexible shingles embodying a shingle laying gauge for accurately laying the shingles.

Figure 2 is a face plan view of my improved self gauging flexible shingle.

Figure 3 is an inverted plan view of my improved self gauging flexible shingle, and

Figure 4 is an edge view of the self gauging shingle.

In the drawing 5 indicates the sheathing

of a roof and 6, 6 my improved self gauging flexible shingles. The roof sheathing 5 may also represent the sheathing on the outer walls of a building.

The flexible shingles 6, 6 are constructed as shown in my previous patent referred to, of a flexible material and each have a bent under lower corner flap 7 with a transverse fastening wire 8 having outwardly extending side ends 9, 9, as shown in Figure 3, which go under the angular lower shingle edges 10, 10, as shown in Figure 1, of shingles previously laid, to hold down the lower end of the shingle. The shingle is square in form and has a flat back 11, a flat face 12, preferably of ground slate, straight lower angular edges 10, 10, straight upper angular edges 13, 13 and side corners 14, 14, as shown in Figures 2 and 3.

In constructing my improved flexible shingle and shingle laying gauge, I fold over the upper end corner of the shingle and form the same into a raised overlying gauge flap 15, which lies flat on the face 12 of the shingle and is preferably the same size and shape as the lower fastening flap 7. This raised overthrown gauge flap 15 with its straight raised gauge edges 16 and 17, at right angles to each other, forms the shingle laying gauge of the shingle.

In laying and fastening the shingles each course of shingles is laid, secured and nailed as described in my previous patent referred to. By the use of my improved shingle with its shingle laying gauge, each next upper course of shingles is laid by placing each shingle so that the adjacent upper angular edge 13, of a shingle on the left will come against the gauge edge 16 and the adjacent upper angular edge 13 of a shingle on the right will come against the gauge edge 17, on the overlying gauge flap 15, the corners 14, 14 of the left and right shingles touching each other and also touching the corner of the overlying gauge flap 15, as shown in Figure 1. This is repeated in laying the course of shingles and in laying each following course of shingles, the shingle laying gauges bringing each shingle into its correct position on the roof and the angular lines formed by the angular edges 10, 10 and 13, 13 of the shingles are thus made straight and true, when the shingling of the roof is completed.

By this construction the shingle laying

gauge is formed integral with the shingle, without waste of material and without increased cost of manufacturing the shingle.

Having thus described my invention I claim as new:

1. A shingle adapted to be laid diagonally and having an upper overturned corner flap, said overturned corner flap lying flat on the face of the shingle and forming a shingle laying gauge, for the purpose as described.

2. A shingle adapted to be laid diagonally and having an upper turned over corner flap, said turned over corner flap lying flat on the face of the shingle and having straight raised gauge edges at right angles to each other, all formed integral, for the purpose as described.

In testimony whereof, I have signed my name to this specification.

ALBERT ABBE GRISWOLD.
